US0D1033620S

(12) **United States Design Patent** (10) **Patent No.:** **US D1,033,620 S**
(45) **Date of Patent:** **** Jul. 2, 2024**

(54) **FAN**

(71) Applicant: **Delta Electronics, Inc.**, Taoyuan (TW)

(72) Inventors: **Chin-Hung Lee**, Taoyuan (TW);
Chieh-Shih Chang, Taoyuan (TW);
Chieh-Hung Chang, Taoyuan (TW)

(73) Assignee: **DELTA ELECTRONICS, INC.**,
Taoyuan (TW)

(**) Term: **15 Years**

(21) Appl. No.: **29/829,340**

(22) Filed: **Mar. 4, 2022**

(51) LOC (14) Cl. **23-04**

(52) U.S. Cl.

USPC **D23/370**

(74) *Attorney, Agent, or Firm* — KIRTON McCONKIE;
Evan R. Witt

(57) **CLAIM**

The ornamental design for a fan, as shown and described.

DESCRIPTION

FIG. 1 is a perspective view of a first embodiment of a fan showing our new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of a second embodiment of a fan showing our new design;

FIG. 10 is another perspective view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof; and,

FIG. 16 is a bottom plan view thereof.

The broken lines in the figures show portions of the fan that form no part of the claimed design.

1 Claim, 12 Drawing Sheets
